UNITED STATES PATENT OFFICE.

WESLEY H. BAUCK, OF CAMDEN, NEW JERSEY.

TOWEL RACK.

Application filed September 29, 1922. Serial No. 591,258.

To all whom it may concern:

Be it known that I, WESLEY H. BAUCK, a citizen of the United States, residing at Camden, in the county of Camden and State 5 of New Jersey, have invented new and useful Improvements in Towel Racks, of which the following is a specification.

My invention relates to new and useful improvements in a towel rack, and has for 10 its object to provide a unique means to fasten the rack to a bath tub or like article.

Another object of this invention is to provide a fastening device in which the adjusting means is invisible after the standard is 15 placed in position.

A further object of my invention is to provide for spacing the rack from the wall of the building such spacing means also adding rigidity to the rack.

With these ends in view, this invention 20 consists in the details of construction and combination of elements hereinafter set forth and then specifically designated by the claims.

In order that those skilled in the art to which this invention appertains, may understand how to make and use the same, I will describe its construction in detail, referring by numerals to the accompanying drawings 30 forming a part of this application, in which:—

Fig. 1, is a sectional side elevation of my improved towel rack showing it attached to the rim of a bath tub which is illustrated in 35 section.

Fig. 2, is a plan view of the head of the rack with the arm broken off.

Fig. 3, is a side elevation of the lower end 40 of the rack at right angles to the showing in Fig. 1, a portion of the tub looking from the inside being illustrated.

Fig. 4, is an enlarged sectional elevation of the body with certain of its component parts illustrating constructional details.

In carrying out my invention as here embodied, 2 represents the oppositely disposed 45 legs supporting the body 3 and adapted to rest upon the upper side of the roll rim or flange 4 of the bath tub 5. The undersides 50 of the legs or the feet forming an integral part thereof are concaved or recessed as at 6 to better fit the curvature of the roll rim.

The body 3 has a vertical bore 7 there- 55 through of two different diameters, the larger portion of said bore containing

threads 8 whereby the lower end of the tubular standard or upright 9 may be screwed therein. The shank 10 of the hook shaped attaching member 11 passes through said bore and has a tubular sleeve 12 loosely fitting over it with the lower end of said sleeve resting on the shoulder 13 produced by the differences in the diameter of the bore while the upper end of said sleeve is below the upper end of the shank. A nut 14 is threaded onto the shank of the attaching member 60 and engages the upper end of the sleeve so that when said nut is rotated in the proper direction the hook end of the attaching member will be drawn toward the body 3 as 65 70 will be obvious.

The hook end of the attaching member is adapted to engage the edge of the roll rim or flange 4 of a tub or the like when the legs are resting on top of said rim and by drawing up on the nut 14 the rack will be secured 75 to the tub. As the attaching member 11 is tightened it has a tendency to force the rack out of a vertical line and in order to prevent this or properly space the rack from the 80 wall, represented by 15, and add rigidity to the structure I provide a spacing device consisting of a plate 16 adapted to rest against the wall or other surface and having threaded connection with a stem 17 which 85 removably fits in the horizontal smooth hole 18 in the body the said stem 17 resting against the inner end of the hole or against the shank of the attaching member where 90 said hole runs into the bore 7 as here 95 shown.

After the body and its component parts are secured to the tub as herein set forth and properly spaced from the wall, the tubular standard 9 is placed over the projecting end of the shank, sleeve and nut and 95 screwed into the larger portion of the bore 7 thus enclosing said parts so that they will be invisible and cannot be tampered with by children or other curious persons. 100

A head 18 is carried by the upper end of the standard and preferably has threaded connection therewith. This head has the arms 19 mounted thereon to support towels, wash rags and the like, said arms being stationary or movable as desired but the latter are here shown for convenience of illustration. 105

The arms may be of any desirable shape, size or configuration and are connected with 110

the rotatable members 20 rotatably mounted upon the pintles 21 set in the head 18 and held in place by the anchoring pins 22.

Of course I do not wish to be limited to the exact details of construction as herein shown as these may be varied within the limits of the appended claims without departing from the spirit of my invention.

Having thus fully described my invention, what I claim as new and useful is:—

1. In a towel rack, a body, legs for supporting said body, an attaching member having a portion passing through said body, means to adjust said attaching member and a standard carrying arms and detachably connected to the body so as to enclose the adjusting means.

2. A towel rack comprising a body having a vertical bore of two different diameters thereby producing a shoulder, the larger portion of the bore being threaded and located above the smaller portion and a horizontal hole, oppositely disposed legs projecting from the body and having concaved under surfaces at their lower ends to rest upon the roll rim of a tub or like object, a hooked attaching member adapted to engage the edge of said rim and having a shank passing through the bore of said body, a tubular sleeve loosely fitting over a portion of said shank and resting on the shoulder within the body with its upper end below the outer end of the shank, a nut having threaded connection with the shank and engaging the upper end of the sleeve to adjust the attaching member, a tubular standard telescoping over the shank, sleeve and nut and screwed into the larger portion of the bore in the body, a head on the upper end of the standard, arms carried by said head, a stem removably fitting in the horizontal hole in the body and a plate adjustably carried by said stem to engage a surface for spacing the rack from said surface and adding rigidity thereto.

telescoping over the shank, sleeve and nut and screwed into the larger portion of the bore in the body, a head on the upper end of the standard, arms carried by said head and means to space the rack from a wall.

3. A towel rack comprising a body having a vertical bore of two different diameters thereby producing a shoulder, the larger portion of the bore being threaded and located above the smaller portion and a horizontal hole, oppositely disposed legs projecting from the body and having concaved under surfaces at their lower ends to rest upon the roll rim of a tub or like object, a hooked attaching member adapted to engage the edge of said rim and having a shank passing through the bore of the body, a tubular sleeve loosely fitting over a portion of said shank and resting on the shoulder within the body with its upper end below the outer end of the shank, a nut having threaded connection with the shank and engaging the upper end of the sleeve to adjust the attaching member, a tubular standard telescoping over the shank, sleeve and nut and screwed into the larger portion of the bore in the body, a head on the upper end of the standard, arms carried by said head, a stem removably fitting in the horizontal hole in the body and a plate adjustably carried by said stem to engage a surface for spacing the rack from said surface and adding rigidity thereto.

In testimony whereof, I have hereunto affixed my signature.

WESLEY H. BAUCK.
